SIGNAL RECEIVING SYSTEM

James M. Kane, Berkeley, Calif.

Application July 26, 1933, Serial No. 682,289

6 Claims. (Cl. 250—8)

(Granted under the act of March 3, 1883, as
amended April 30, 1928; 370 O. G. 757)

My invention relates broadly to signal receiving systems and more particularly to a high speed relay circuit for operation in a signal receiving system.

5 One of the objects of my invention is to provide a circuit arrangement for a high speed relay system for insuring accurate operation of a circuit closing device in a high frequency receiving circuit at high speed.

10 Another object of my invention is to provide a circuit arrangement for a high speed radio telegraph receiving system wherein a high frequency oscillator at a receiving station may be keyed by incoming signals for in turn controlling

15 the operation of a relay for the actuation of a recording apparatus at the receiving station, substantially independent of the amplitude of the incoming signaling energy.

Still another object of my invention is to provide a circuit arrangement including a source of 20 audible oscillations which may be keyed by incoming telegraphic signals for actuating a relay circuit adapted to control any form of recording apparatus.

25 A further object of my invention is to provide a relay circuit arrangement for telegraphic receiving systems in which an audible oscillator may be controlled by incoming telegraphic signals of relatively feeble amplitude for controlling 30 at any desired amplitude the operation of a recording apparatus connected with the relay circuit controlled by the audible oscillator.

A still further object of my invention is to provide a circuit arrangement for a signal receiving 35 system in which an audible oscillator is keyed by incoming signaling energy to in turn control the operation of a relay circuit in combination with means for checking the operation of the audible oscillator in order that the operating 40 characteristics of the audible oscillator may be readily determined for observing the operation of the relay circuit controlled by the audible oscillator.

45 Other and further objects of my invention reside in a circuit arrangement for a high speed relay system for telegraphic reception as set forth more fully in the specification hereinafter following by reference to the accompanying drawings which diagrammatically illustrates the circuit of my invention.

The system of my invention is directed particularly to a circuit for an audio frequency unit 50 which is connected to the output of a power amplifier in a radio telegraph receiving system or in a carrier frequency line wire telegraph system.

I have successfully used the apparatus of my invention in radio circuits employing the Baudot code for operation of automatic printer apparatus known as the Teletype. The apparatus of my invention has been successfully operated at 60 Radio Central, in the U. S. Navy Building, at Washington, D. C., for controlling an automatic printer by radio impulses transmitted from the U. S. Navy high power radio station at Mare Island, California. I provide a polarized relay 65 circuit which responds to the audio frequency impulses delivered by the output of a power amplifier. The polarized relay circuit modulates or keys an audible oscillator from its back or normally closed contacts. The output of the audible oscillator is coupled to a second polarized relay circuit which keys or operates the apparatus that requires the Baudot code such as the Teletype. The audible oscillator connects to the second polarized relay device and also to a telephone 70 circuit by which the operation of the audible oscillator can be periodically checked. The advantages of this cascade relay circuit are two-fold. First, the operation of the relay system can be monitored by listening to the audible oscillator. Second, the circuit becomes more capable of adjustment for the following reason: The adjustments of the last relay circuit are made as desired and then fixed. This part of the circuit 75 can be assumed to be incapable of misfiring when the oscillator delivers a proper impulse. Where relays and long control lines are used to key a radio transmitter, the inductance of the coils, and the capacity of the lines will change the shape of the transmitter emission. The characters may not be clear cut with perpendicular ends, but may slant or be chopped off, showing a lagging relay action. This unsatisfactory keying 80 will not operate apparatus utilizing the Baudot code for the "blacks" and "whites" are thrown out of proportion and shape. Any unfaithfulness 85 of transmitted relays can be immediately detected by listening to the audible oscillator of this circuit and it can be compensated for by the adjustments of the bias of the electron tubes in 90 the circuit of my invention. A character shortened by faulty transmitter relay action can, therefore, be corrected and brought to its normal shape, simultaneously correcting the time interval or "white" between the "blacks" or transmitted characters.

95 Referring to the drawing in detail, reference character 1 designates the input circuit to the primary winding 2 of an audio frequency transformer 3. The secondary winding 4 of the audio 100 transformer 3 is connected to the primary winding 5 of a polarized relay 6. The secondary winding 7 of the polarized relay 6 is connected to the primary winding 8 of a second polarized relay 9. The secondary winding 10 of the second polarized relay 9 is connected to the primary winding 11 of a third polarized relay 12. The secondary winding 13 of the third polarized relay 12 is connected to the primary winding 14 of a fourth polarized relay 15. The secondary winding 16 of the fourth polarized relay 15 is connected to the primary winding 17 of a fifth polarized relay 18. The secondary winding 19 of the fifth polarized relay 18 is connected to the primary winding 20 of a sixth polarized relay 21. The secondary winding 22 of the sixth polarized relay 21 is connected to the primary winding 23 of a seventh polarized relay 24. The secondary winding 25 of the seventh polarized relay 24 is connected to the primary winding 26 of an eighth polarized relay 27. The secondary winding 28 of the eighth polarized relay 27 is connected to the primary winding 29 of a ninth polarized relay 30. The secondary winding 31 of the ninth polarized relay 30 is connected to the primary winding 32 of a tenth polarized relay 33. The secondary winding 34 of the tenth polarized relay 33 is connected to the primary winding 35 of a eleventh polarized relay 36. The secondary winding 37 of the eleventh polarized relay 36 is connected to the primary winding 38 of a twelfth polarized relay 39. The secondary winding 40 of the twelfth polarized relay 39 is connected to the primary winding 41 of a thirteenth polarized relay 42. The secondary winding 43 of the thirteenth polarized relay 42 is connected to the primary winding 44 of a fourteenth polarized relay 45. The secondary winding 46 of the fourteenth polarized relay 45 is connected to the primary winding 47 of a fifteenth polarized relay 48. The secondary winding 49 of the fifteenth polarized relay 48 is connected to the primary winding 50 of a sixteenth polarized relay 51. The secondary winding 52 of the sixteenth polarized relay 51 is connected to the primary winding 53 of a seventeenth polarized relay 54. The secondary winding 55 of the seventeenth polarized relay 54 is connected to the primary winding 56 of a eighteenth polarized relay 57. The secondary winding 58 of the eighteenth polarized relay 57 is connected to the primary winding 59 of a nineteenth polarized relay 60. The secondary winding 61 of the nineteenth polarized relay 60 is connected to the primary winding 62 of a twentieth polarized relay 63. The secondary winding 64 of the twentieth polarized relay 63 is connected to the primary winding 65 of a twenty-first polarized relay 66. The secondary winding 67 of the twenty-first polarized relay 66 is connected to the primary winding 68 of a twenty-second polarized relay 69. The secondary winding 70 of the twenty-second polarized relay 69 is connected to the primary winding 71 of a twenty-third polarized relay 72. The secondary winding 73 of the twenty-third polarized relay 72 is connected to the primary winding 74 of a twenty-fourth polarized relay 75. The secondary winding 76 of the twenty-fourth polarized relay 75 is connected to the primary winding 77 of a twenty-fifth polarized relay 78. The secondary winding 79 of the twenty-fifth polarized relay 78 is connected to the primary winding 80 of a twenty-sixth polarized relay 81. The secondary winding 82 of the twenty-sixth polarized relay 81 is connected to the primary winding 83 of a twenty-seventh polarized relay 84. The secondary winding 85 of the twenty-seventh polarized relay 84 is connected to the primary winding 86 of a twenty-eighth polarized relay 87. The secondary winding 88 of the twenty-eighth polarized relay 87 is connected to the primary winding 89 of a twenty-ninth polarized relay 90. The secondary winding 91 of the twenty-ninth polarized relay 90 is connected to the primary winding 92 of a thirtieth polarized relay 93. The secondary winding 94 of the thirtieth polarized relay 93 is connected to the primary winding 95 of a thirty-first polarized relay 96. The secondary winding 97 of the thirty-first polarized relay 96 is connected to the primary winding 98 of a thirty-second polarized relay 99. The secondary winding 100 of the thirty-second polarized relay 99 is connected to the primary winding 101 of a thirty-third polarized relay 102. The secondary winding 103 of the thirty-third polarized relay 102 is connected to the primary winding 104 of a thirty-fourth polarized relay 105. The secondary winding 106 of the thirty-fourth polarized relay 105 is connected to the primary winding 107 of a thirty-fifth polarized relay 108. The secondary winding 109 of the thirty-fifth polarized relay 108 is connected to the primary winding 110 of a thirty-sixth polarized relay 111. The secondary winding 112 of the thirty-sixth polarized relay 111 is connected to the primary winding 113 of a thirty-seventh polarized relay 114. The secondary winding 115 of the thirty-seventh polarized relay 114 is connected to the primary winding 116 of a thirty-eighth polarized relay 117. The secondary winding 118 of the thirty-eighth polarized relay 117 is connected to the primary winding 119 of a thirty-ninth polarized relay 120. The secondary winding 121 of the thirty-ninth polarized relay 120 is connected to the primary winding 122 of a forty-first polarized relay 123. The secondary winding 124 of the forty-first polarized relay 123 is connected to the primary winding 125 of a forty-second polarized relay 126. The secondary winding 127 of the forty-second polarized relay 126 is connected to the primary winding 128 of a forty-third polarized relay 129. The secondary winding 130 of the forty-third polarized relay 129 is connected to the primary winding 131 of a forty-fourth polarized relay 132. The secondary winding 133 of the forty-fourth polarized relay 132 is connected to the primary winding 134 of a forty-fifth polarized relay 135. The secondary winding 136 of the forty-fifth polarized relay 135 is connected to the primary winding 137 of a forty-sixth polarized relay 138. The secondary winding 139 of the forty-sixth polarized relay 138 is connected to the primary winding 140 of a forty-seventh polarized relay 141. The secondary winding 142 of the forty-seventh polarized relay 141 is connected to the primary winding 143 of a forty-eighth polarized relay 144. The secondary winding 145 of the forty-eighth polarized relay 144 is connected to the primary winding 146 of a forty-ninth polarized relay 147. The secondary winding 148 of the forty-ninth polarized relay 147 is connected to the primary winding 149 of a fifty-first polarized relay 150. The secondary winding 151 of the fifty-first polarized relay 150 is connected to the primary winding 152 of a fifty-second polarized relay 153. The secondary winding 154 of the fifty-second polarized relay 153 is connected to the primary winding 155 of a fifty-third polarized relay 156. The secondary winding 157 of the fifty-third polarized relay 156 is connected to the primary winding 158 of a fifty-fourth polarized relay 159. The secondary winding 160 of the fifty-fourth polarized relay 159 is connected to the primary winding 161 of a fifty-fifth polarized relay 162. The secondary winding 164 of the fifty-fifth polarized relay 162 is connected to the primary winding 165 of a fifty-sixth polarized relay 166. The secondary winding 168 of the fifty-sixth polarized relay 166 is connected to the primary winding 169 of a fifty-seventh polarized relay 170. The secondary winding 172 of the fifty-seventh polarized relay 170 is connected to the primary winding 173 of a fifty-eighth polarized relay 174. The secondary winding 176 of the fifty-eighth polarized relay 174 is connected to the primary winding 177 of a fifty-ninth polarized relay 178. The secondary winding 180 of the fifty-ninth polarized relay 178 is connected to the primary winding 181 of a sixty-first polarized relay 182. The secondary winding 184 of the sixty-first polarized relay 182 is connected to the primary winding 185 of a sixty-second polarized relay 186. The secondary winding 188 of the sixty-second polarized relay 186 is connected to the primary winding 189 of a sixty-third polarized relay 190. The secondary winding 192 of the sixty-third polarized relay 190 is connected to the primary winding 193 of a sixty-fourth polarized relay 194. The secondary winding 196 of the sixty-fourth polarized relay 194 is connected to the primary winding 197 of a sixty-fifth polarized relay 198. The secondary winding 200 of the sixty-fifth polarized relay 198 is connected to the primary winding 201 of a sixty-sixth polarized relay 202. The secondary winding 204 of the sixty-sixth polarized relay 202 is connected to the primary winding 205 of a sixty-seventh polarized relay 206. The secondary winding 208 of the sixty-seventh polarized relay 206 is connected to the primary winding 209 of a sixty-eighth polarized relay 210. The secondary winding 212 of the sixty-eighth polarized relay 210 is connected to the primary winding 213 of a sixty-ninth polarized relay 214. The secondary winding 216 of the sixty-ninth polarized relay 214 is connected to the primary winding 217 of a seventy-first polarized relay 218. The secondary winding 220 of the seventy-first polarized relay 218 is connected to the primary winding 221 of a seventy-second polarized relay 222. The secondary winding 224 of the seventy-second polarized relay 222 is connected to the primary winding 225 of a seventy-third polarized relay 226. The secondary winding 228 of the seventy-third polarized relay 226 is connected to the primary winding 229 of a seventy-fourth polarized relay 230. The secondary winding 232 of the seventy-fourth polarized relay 230 is connected to the primary winding 233 of a seventy-fifth polarized relay 234. The secondary winding 236 of the seventy-fifth polarized relay 234 is connected to the primary winding 237 of a seventy-sixth polarized relay 238. The secondary winding 240 of the seventy-sixth polarized relay 238 is connected to the primary winding 241 of a seventy-seventh polarized relay 242. The secondary winding 244 of the seventy-seventh polarized relay 242 is connected to the primary winding 245 of a seventy-eighth polarized relay 246. The secondary winding 248 of the seventy-eighth polarized relay 246 is connected to the primary winding 249 of a seventy-ninth polarized relay 250. The secondary winding 252 of the seventy-ninth polarized relay 250 is connected to the primary winding 253 of a eighty-first polarized relay 254. The secondary winding 256 of the eighty-first polarized relay 254 is connected to the primary winding 257 of a eighty-second polarized relay 258. The secondary winding 260 of the eighty-second polarized relay 258 is connected to the primary winding 261 of a eighty-third polarized relay 262. The secondary winding 264 of the eighty-third polarized relay 262 is connected to the primary winding 265 of a eighty-fourth polarized relay 266. The secondary winding 268 of the eighty-fourth polarized relay 266 is connected to the primary winding 269 of a eighty-fifth polarized relay 270. The secondary winding 272 of the eighty-fifth polarized relay 270 is connected to the primary winding 273 of a eighty-sixth polarized relay 274. The secondary winding 276 of the eighty-sixth polarized relay 274 is connected to the primary winding 277 of a eighty-seventh polarized relay 278. The secondary winding 280 of the eighty-seventh polarized relay 278 is connected to the primary winding 281 of a eighty-eighth polarized relay 282. The secondary winding 284 of the eighty-eighth polarized relay 282 is connected to the primary winding 285 of a eighty-ninth polarized relay 286. The secondary winding 288 of the eighty-ninth polarized relay 286 is connected to the primary winding 289 of a ninety-first polarized relay 290. The secondary winding 292 of the ninety-first polarized relay 290 is connected to the primary winding 293 of a ninety-second polarized relay 294. The secondary winding 296 of the ninety-second polarized relay 294 is connected to the primary winding 297 of a ninety-third polarized relay 298. The secondary winding 300 of the ninety-third polarized relay 298 is connected to the primary winding 301 of a ninety-fourth polarized relay 302. The secondary winding 304 of the ninety-fourth polarized relay 302 is connected to the primary winding 305 of a ninety-fifth polarized relay 306. The secondary winding 308 of the ninety-fifth polarized relay 306 is connected to the primary winding 309 of a ninety-sixth polarized relay 310. The secondary winding 312 of the ninety-sixth polarized relay 310 is connected to the primary winding 313 of a ninety-seventh polarized relay 314. The secondary winding 316 of the ninety-seventh polarized relay 314 is connected to the primary winding 317 of a ninety-eighth polarized relay 318. The secondary winding 320 of the ninety-eighth polarized relay 318 is connected to the primary winding 321 of a ninety-ninth polarized relay 322. The secondary winding 324 of the ninety-ninth polarized relay 322 is connected to the primary winding 325 of a one-hundredth polarized relay 326. The secondary winding 328 of the one-hundredth polarized relay 326 is connected to the primary winding 329 of a one-hundred-first polarized relay 330. The secondary winding 332 of the one-hundred-first polarized relay 330 is connected to the primary winding 333 of a one-hundred-second polarized relay 334. The secondary winding 336 of the one-hundred-second polarized relay 334 is connected to the primary winding 337 of a one-hundred-third polarized relay 338. The secondary winding 340 of the one-hundred-third polarized relay 338 is connected to the primary winding 341 of a one-hundred-fourth polarized relay 342. The secondary winding 344 of the one-hundred-fourth polarized relay 342 is connected to the primary winding 345 of a one-hundred-fifth polarized relay 346. The secondary winding 348 of the one-hundred-fifth polarized relay 346 is connected to the primary winding 349 of a one-hundred-sixth polarized relay 350. The secondary winding 352 of the one-hundred-sixth polarized relay 350 is connected to the primary winding 353 of a one-hundred-seventh polarized relay 354. The secondary winding 356 of the one-hundred-seventh polarized relay 354 is connected to the primary winding 357 of a one-hundred-eighth polarized relay 358. The secondary winding 360 of the one-hundred-eighth polarized relay 358 is connected to the primary winding 361 of a one-hundred-ninth polarized relay 362. The secondary winding 364 of the one-hundred-ninth polarized relay 362 is connected to the primary winding 365 of a one-hundred-tenth polarized relay 366. The secondary winding 368 of the one-hundred-tenth polarized relay 366 is connected to the primary winding 369 of a one-hundred-eleventh polarized relay 370. The secondary winding 372 of the one-hundred-eleventh polarized relay 370 is connected to the primary winding 373 of a one-hundred-twelfth polarized relay 374. The secondary winding 376 of the one-hundred-twelfth polarized relay 374 is connected to the primary winding 377 of a one-hundred-thirteenth polarized relay 378. The secondary winding 380 of the one-hundred-thirteenth polarized relay 378 is connected to the primary winding 381 of a one-hundred-fourteenth polarized relay 382. The secondary winding 384 of the one-hundred-fourteenth polarized relay 382 is connected to the primary winding 385 of a one-hundred-fifteenth polarized relay 386. The secondary winding 388 of the one-hundred-fifteenth polarized relay 386 is connected to the primary winding 389 of a one-hundred-sixteenth polarized relay 390. The secondary winding 392 of the one-hundred-sixteenth polarized relay 390 is connected to the primary winding 393 of a one-hundred-seventeenth polarized relay 394. The secondary winding 396 of the one-hundred-seventeenth polarized relay 394 is connected to the primary winding 397 of a one-hundred-eighteenth polarized relay 398. The secondary winding 400 of the one-hundred-eighteenth polarized relay 398 is connected to the primary winding 401 of a one-hundred-nineteenth polarized relay 402. The secondary winding 404 of the one-hundred-nineteenth polarized relay 402 is connected to the primary winding 405 of a one-hundred-twentieth polarized relay 406. The secondary winding 408 of the one-hundred-twentieth polarized relay 406 is connected to the primary winding 409 of a one-hundred-twenty-first polarized relay 410. The secondary winding 412 of the one-hundred-twenty-first polarized relay 410 is connected to the primary winding 413 of a one-hundred-twenty-second polarized relay 414. The secondary winding 416 of the one-hundred-twenty-second polarized relay 414 is connected to the primary winding 417 of a one-hundred-twenty-third polarized relay 418. The secondary winding 420 of the one-hundred-twenty-third polarized relay 418 is connected to the primary winding 421 of a one-hundred-twenty-fourth polarized relay 422. The secondary winding 424 of the one-hundred-twenty-fourth polarized relay 422 is connected to the primary winding 425 of a one-hundred-twenty-fifth polarized relay 426. The secondary winding 428 of the one-hundred-twenty-fifth polarized relay 426 is connected to the primary winding 429 of a one-hundred-twenty-sixth polarized relay 430. The secondary winding 432 of the one-hundred-twenty-sixth polarized relay 430 is connected to the primary winding 433 of a one-hundred-twenty-seventh polarized relay 434. The secondary winding 436 of the one-hundred-twenty-seventh polarized relay 434 is connected to the primary winding 437 of a one-hundred-twenty-eighth polarized relay 438. The secondary winding 440 of the one-hundred-twenty-eighth polarized relay 438 is connected to the primary winding 441 of a one-hundred-twenty-ninth polarized relay 442. The secondary winding 444 of the one-hundred-twenty-ninth polarized relay 442 is connected to the primary winding 445 of a one-hundred-twenty-tenth polarized relay 446. The secondary winding 448 of the one-hundred-twenty-tenth polarized relay 446 is connected to the primary winding 449 of a one-hundred-twenty-eleventh polarized relay 450. The secondary winding 452 of the one-hundred-twenty-eleventh polarized relay 450 is connected to the primary winding 453 of a one-hundred-twenty-twelfth polarized relay 454. The secondary winding 456 of the one-hundred-twenty-twelfth polarized relay 454 is connected to the primary winding 457 of a one-hundred-twenty-thirteenth polarized relay 458. The secondary winding 460 of the one-hundred-twenty-thirteenth polarized relay 458 is connected to the primary winding 461 of a one-hundred-twenty-fourth polarized relay 462. The secondary winding 464 of the one-hundred-twenty-fourth polarized relay 462 is connected to the primary winding 465 of a one-hundred-twenty-fifth polarized relay 466. The secondary winding 468 of the one-hundred-twenty-fifth polarized relay 466 is connected to the primary winding 469 of a one-hundred-twenty-sixth polarized relay 470. The secondary winding 472 of the one-hundred-twenty-sixth polarized relay 470 is connected to the primary winding 473 of a one-hundred-twenty-seventh polarized relay 474. The secondary winding 476 of the one-hundred-twenty-seventh polarized relay 474 is connected to the primary winding 477 of a one-hundred-twenty-eighth polarized relay 478. The secondary winding 480 of the one-hundred-twenty-eighth polarized relay 478 is connected to the primary winding 481 of a one-hundred-twenty-ninth polarized relay 482. The secondary winding 484 of the one-hundred-twenty-ninth polarized relay 482 is connected to the primary winding 485 of a one-hundred-twenty-tenth polarized relay 486. The secondary winding 488 of the one-hundred-twenty-tenth polarized relay 486 is connected to the primary winding 489 of a one-hundred-twenty-eleventh polarized relay 490. The secondary winding 492 of the one-hundred-twenty-eleventh polarized relay 490 is connected to the primary winding 493 of a one-hundred-twenty-twelfth polarized relay 494. The secondary winding 496 of the one-hundred-twenty-twelfth polarized relay 494 is connected to the primary winding 497 of a one-hundred-twenty-thirteenth polarized relay 498. The secondary winding 500 of the one-hundred-twenty-thirteenth polarized relay 498 is connected to the primary winding 501 of a one-hundred-twenty-fourth polarized relay 502. The secondary winding 504 of the one-hundred-twenty-fourth polarized relay 502 is connected to the primary winding 505 of a one-hundred-twenty-fifth polarized relay 506. The secondary winding 508 of the one-hundred-twenty-fifth polarized relay 506 is connected to the primary winding 509 of a one-hundred-twenty-sixth polarized relay 510. The secondary winding 512 of the one-hundred-twenty-sixth polarized relay 510 is connected to the primary winding 513 of a one-hundred-twenty-seventh polarized relay 514. The secondary winding 516 of the one-hundred-twenty-seventh polarized relay 514 is connected to the primary winding 517 of a one-hundred-twenty-eighth polarized relay 518. The secondary winding 520 of the one-hundred-twenty-eighth polarized relay 518 is connected to the primary winding 521 of a one-hundred-twenty-ninth polarized relay 522. The secondary winding 524 of the one-hundred-twenty-ninth polarized relay 522 is connected to the primary winding 525 of a one-hundred-twenty-tenth polarized relay 526. The secondary winding 528 of the one-hundred-twenty-tenth polarized relay 526 is connected to the primary winding 529 of a one-hundred-twenty-eleventh polarized relay 530. The secondary winding 532 of the one-hundred-twenty-eleventh polarized relay 530 is connected to the primary winding 533 of a one-hundred-twenty-twelfth polarized relay 534. The secondary winding 536 of the one-hundred-twenty-twelfth polarized relay 534 is connected to the primary winding 537 of a one-hundred-twenty-thirteenth polarized relay 538. The secondary winding 540 of the one-hundred-twenty-thirteenth polarized relay 538 is connected to the primary winding 541 of a one-hundred-twenty-fourth polarized relay 542. The secondary winding 544 of the one-hundred-twenty-fourth polarized relay 542 is connected to the primary winding 545 of a one-hundred-twenty-fifth polarized relay 546. The secondary winding 548 of the one-hundred-twenty-fifth polarized relay 546 is connected to the primary winding 549 of a one-hundred-twenty-sixth polarized relay 550. The secondary winding 552 of the one-hundred-twenty-sixth polarized relay 550 is connected to the primary winding 553 of a one-hundred-twenty-seventh polarized relay 554. The secondary winding 556 of the one-hundred-twenty-seventh polarized relay 554 is connected to the primary winding 557 of a one-hundred-twenty-eighth polarized relay 558. The secondary winding 560 of the one-hundred-twenty-eighth polarized relay 558 is connected to the primary winding 561 of a one-hundred-twenty-ninth polarized relay 562. The secondary winding 564 of the one-hundred-twenty-ninth polarized relay 562 is connected to the primary winding 565 of a one-hundred-twenty-tenth polarized relay 566. The secondary winding 568 of the one-hundred-twenty-tenth polarized relay 566 is connected to the primary winding 569 of a one-hundred-twenty-eleventh polarized relay 570. The secondary winding 572 of the one-hundred-twenty-eleventh polarized relay 570 is connected to the primary winding 573 of a one-hundred-twenty-twelfth polarized relay 574. The secondary winding 576 of the one-hundred-twenty-twelfth polarized relay 574 is connected to the primary winding 577 of a one-hundred-twenty-thirteenth polarized relay 578. The secondary winding 580 of the one-hundred-twenty-thirteenth polarized relay 578 is connected to the primary winding 581 of a one-hundred-twenty-fourth polarized relay 582. The secondary winding 584 of the one-hundred-twenty-fourth polarized relay 582 is connected to the primary winding 585 of a one-hundred-twenty-fifth polarized relay 586. The secondary winding 588 of the one-hundred-twenty-fifth polarized relay 586 is connected to the primary winding 589 of a one-hundred-twenty-sixth polarized relay 590. The secondary winding 592 of the one-hundred-twenty-sixth polarized relay 590 is connected to the primary winding 593 of a one-hundred-twenty-seventh polarized relay 594. The secondary winding 596 of the one-hundred-twenty-seventh polarized relay 594 is connected to the primary winding 597 of a one-hundred-twenty-eighth polarized relay 598. The secondary winding 600 of the one-hundred-twenty-eighth polarized relay 598 is connected to the primary winding 601 of a one-hundred-twenty-ninth polarized relay 602. The secondary winding 604 of the one-hundred-twenty-ninth polarized relay 602 is connected to the primary winding 605 of a one-hundred-twenty-tenth polarized relay 606. The secondary winding 608 of the one-hundred-twenty-tenth polarized relay 606 is connected to the primary winding 609 of a one-hundred-twenty-eleventh polarized relay 610. The secondary winding 612 of the one-hundred-twenty-eleventh polarized relay 610 is connected to the primary winding 613 of a one-hundred-twenty-twelfth polarized relay 614. The secondary winding 616 of the one-hundred-twenty-twelfth polarized relay 614 is connected to the primary winding 617 of a one-hundred-twenty-thirteenth polarized relay 618. The secondary winding 620 of the one-hundred-twenty-thirteenth polarized relay 618 is connected to the primary winding 621 of a one-hundred-twenty-fourth polarized relay 622. The secondary winding 624 of the one-hundred-twenty-fourth polarized relay 622 is connected to the primary winding 625 of a one-hundred-twenty-fifth polarized relay 626. The secondary winding 628 of the one-hundred-twenty-fifth polarized relay 626 is connected to the primary winding 629 of a one-hundred-twenty-sixth polarized relay 630. The secondary winding 632 of the one-hundred-twenty-sixth polarized relay 630 is connected to the primary winding 633 of a one-hundred-twenty-seventh polarized relay 634. The secondary winding 636 of the one-hundred-twenty-seventh polarized relay 634 is connected to the primary winding 637 of a one-hundred-twenty-eighth polarized relay 638. The secondary winding 640 of the one-hundred-twenty-eighth polarized relay 638 is connected to the primary winding 641 of a one-hundred-twenty-ninth polarized relay 642. The secondary winding 644 of the one-hundred-twenty-ninth polarized relay 642 is connected to the primary winding 645 of a one-hundred-twenty-tenth polarized relay 646. The secondary winding 648 of the one-hundred-twenty-tenth polarized relay 646 is connected to the primary winding 649 of a one-hundred-twenty-eleventh polarized relay 650. The secondary winding 652 of the one-hundred-twenty-eleventh polarized relay 650 is connected to the primary winding 653 of a one-hundred-twenty-twelfth polarized relay 654. The secondary winding 656 of the one-hundred-twenty-twelfth polarized relay 654 is connected to the primary winding 657 of a one-hundred-twenty-thirteenth polarized relay 658. The secondary winding 660 of the one-hundred-twenty-thirteenth polarized relay 658 is connected to the primary winding 661 of a one-hundred-twenty-fourth polarized relay 662. The secondary winding 664 of the one-hundred-twenty-fourth polarized relay 662 is connected to the primary winding 665 of a one-hundred-twenty-fifth polarized relay 666. The secondary winding 668 of the one-hundred-twenty-fifth polarized relay 666 is connected to the primary winding 669 of a one-hundred-twenty-sixth polarized relay 670. The secondary winding 672 of the one-hundred-twenty-sixth polarized relay 670 is connected to the primary winding 673 of a one-hundred-twenty-seventh polarized relay 674. The secondary winding 676 of the one-hundred-twenty-seventh polarized relay 674 is connected to the primary winding 677 of a one-hundred-twenty-eighth polarized relay 678. The secondary winding 680 of the one-hundred-twenty-eighth polarized relay 678 is connected to the primary winding 681 of a one-hundred-twenty-ninth polarized relay 682. The secondary winding 684 of the one-hundred-twenty-ninth polarized relay 682 is connected to the primary winding 685 of a one-hundred-twenty-tenth polarized relay 686. The secondary winding 688 of the one-hundred-twenty-tenth polarized relay 686 is connected to the primary winding 689 of a one-hundred-twenty-eleventh polarized relay 690. The secondary winding 692 of the one-hundred-twenty-eleventh polarized relay 690 is connected to the primary winding 693 of a one-hundred-twenty-twelfth polarized relay 694. The secondary winding 696 of the one-hundred-twenty-twelfth polarized relay 694 is connected to the primary winding 697 of a one-hundred-twenty-thirteenth polarized relay 698. The secondary winding 698 of the one-hundred-twenty-thirteenth polarized relay 698 is connected to the primary winding 700 of a one-hundred-twenty-fourth polarized relay 702. The secondary winding 704 of the one-hundred-twenty-fourth polarized relay 702 is connected to the primary winding 705 of a one-hundred-twenty-fifth polarized relay 706. The secondary winding 708 of the one-hundred-twenty-fifth polarized relay 706 is connected to the primary winding 709 of a one-hundred-twenty-sixth polarized relay 710. The secondary winding 712 of the one-hundred-twenty-sixth polarized relay 710 is connected to the primary winding 713 of a one-hundred-twenty-seventh polarized relay 714. The secondary winding 716 of the one-hundred-twenty-seventh polarized relay 714 is connected to the primary winding 717 of a one-hundred-twenty-eighth polarized relay 718. The secondary winding 720 of the one-hundred-twenty-eighth polarized relay 718 is connected to the primary winding 721 of a one-hundred-twenty-ninth polarized relay 722. The secondary winding 724 of the one-hundred-twenty-ninth polarized relay 722 is connected to the primary winding 725 of a one-hundred-twenty-tenth polarized relay 726. The secondary winding 728 of the one-hundred-twenty-tenth polarized relay 726 is connected to the primary winding 729 of a one-hundred-twenty-eleventh polarized relay 730. The secondary winding 732 of the one-hundred-twenty-eleventh polarized relay 730 is connected to the primary winding 733 of a one-hundred-twenty-twelfth polarized relay 734. The secondary winding 736 of the one-hundred-twenty-twelfth polarized relay 734 is connected to the primary winding 737 of a one-hundred-twenty-thirteenth polarized relay 738. The secondary winding 740 of the one-hundred-twenty-thirteenth polarized relay 738 is connected to the primary winding 741 of a one-hundred-twenty-fourth polarized relay 742. The secondary winding 744 of the one-hundred-twenty-fourth polarized relay 742 is connected to the primary winding 745 of a one-hundred-twenty-fifth polarized relay 746. The secondary winding 748 of the one-hundred-twenty-fifth polarized relay 746 is connected to the primary winding 749 of a one-hundred-twenty-sixth polarized relay 750. The secondary winding 752 of the one-hundred-twenty-sixth polarized relay 750 is connected to the primary winding 753 of a one-hundred-twenty-seventh polarized relay 754. The secondary winding 756 of the one-hundred-twenty-seventh polarized relay 754 is connected to the primary winding 757 of a one-hundred-twenty-eighth polarized relay 758. The secondary winding 760 of the one-hundred-twenty-eighth polarized relay 758 is connected to the primary winding 761 of a one-hundred-twenty-ninth polarized relay 762. The secondary winding 764 of the one-hundred-twenty-ninth polarized relay 762 is connected to the primary winding 765 of a one-hundred-twenty-tenth polarized relay 766. The secondary winding 768 of the one-hundred-twenty-tenth polarized relay 766 is connected to the primary winding 769 of a one-hundred-twenty-eleventh polarized relay 770. The secondary winding 772 of the one-hundred-twenty-eleventh polarized relay 770 is connected to the primary winding 773 of a one-hundred-twenty-twelfth polarized relay 774. The secondary winding 776 of the one-hundred-twenty-twelfth polarized relay 774 is connected to the primary winding 777 of a one-hundred-twenty-thirteenth polarized relay 778. The secondary winding 780 of the one-hundred-twenty-thirteenth polarized relay 778 is connected to the primary winding 781 of a one-hundred-twenty-fourth polarized relay 782. The secondary winding 784 of the one-hundred-twenty-fourth polarized relay 782 is connected to the primary winding 785 of a one-hundred-twenty-fifth polarized relay 786. The secondary winding 788 of the one-hundred-twenty-fifth polarized relay 786 is connected to the primary winding 789 of a one-hundred-twenty-sixth polarized relay 790. The secondary winding 792 of the one-hundred-twenty-sixth polarized relay 790 is connected to the primary winding 793 of a one-hundred-twenty-seventh polarized relay 794. The secondary winding 796 of the one-hundred-twenty-seventh polarized relay 794 is connected to the primary winding 797 of a one-hundred-twenty-eighth polarized relay 798. The secondary winding 800 of the one-hundred-twenty-eighth polarized relay 798 is connected to the primary winding 801 of a one-hundred-twenty-ninth polarized relay 802. The secondary winding 804 of the one-hundred-twenty-ninth polarized relay 802 is connected to the primary winding 805 of a one-hundred-twenty-tenth polarized relay 806. The secondary winding 808 of the one-hundred-twenty-tenth polarized relay 806 is connected to the primary winding 809 of a one-hundred-twenty-eleventh polarized relay 810.

frequency transformer 3 connects to the input circuit of electron tube 5. Electron tube 5 includes a cathode 5a, control grid 5b and an anode 5c. The grid circuit is adjustably biased from battery 6 shunted by potentiometer 7 with tap connection 8. Cathode 5a is heated from any suitable source of potential, which I have designated generally at 9. The output circuit of tube 5 contains milliammeter 62 and actuating coil 10 of polarized relay 12. The output circuit of tube 5 also includes resistor 11 and the source of potential 14 returning to the cathode circuit adjacent the source 9. A second electron tube 15 is provided having its input circuit leading from cathode 15a and control grid 15b connected across resistor 11 through the bias adjusting means constituted by battery 16, potentiometer 17 and adjustable tap 18. The output circuit of electron tube 15 extends from anode 15c through milliammeter 19 through actuator 20 of polarized relay 12 to the positive side of the source of potential 21. The cathode 15a of electron tube 15 is heated from suitable source of potential represented at 22. Armature 23 is controlled by actuating windings 10 and 20 of polarized relay 12 coating with the core structure 12a. A set of contacts 24 are alternately opened and closed by operation of the relay system. An audible oscillator is shown at 25 constituted by electron tube 26 having cathode 26a, grid electrode 26b and anode 26c. The input circuit of electron tube 26 between grid electrode 26b and cathode 26a is closed through inductance 27. The inductance 27 is wound upon an iron core 28 and is inductively coupled with winding 29. Winding 29 is connected in the output circuit of electron tube 26 between anode 26c and in series with resistance element 30 to the connection 31 which leads to the positive side of the source of potential 21, the circuit being completed through lead 32 to lead 33 which is connected with cathode 26a, thereby completing the output circuit of the oscillator tube 26. The output of the oscillator 26 also is coupled through a condenser 34 and an impedance 35 with the input circuit of an electron tube 36. Electron tube 36 includes cathodes 36a, control grid 36b and anode 36c. The input circuit of electron tube 36 is completed from control grid 36b through impedance 35 through the adjustable tap 37 on potentiometer 38, which connects in shunt with battery 39. This bias control circuit connects to cathode circuit 6a as shown. The output of electron tube 36 connects through milliammeter 41 through actuating winding 40 of polarized relay 42 and through resistor 43 to the source of potential 14, the circuit being completed through lead 44 which returns to the cathode 36a. I employ the same source of potential 14 for the output of tube 36 as is provided for the output of tube 5. It is clear however that independent sources of plate potential may be used as desired. The input circuit for electron tube 45 extends from cathode 45a through lead 46, lead 33, lead 32, lead 47 through resistor 43, lead 48, and bias control 49 to the control grid 45b. The output circuit of tube 45 extends from anode 45c through milliammeter 51 to actuating winding 50 of polarized relay 42 through lead 52, lead 31, through source of plate potential 21, returning through lead 32 and lead 33, to lead 46 and cathode 45a. It will be observed that cathodes 45a, 26a and 15a are all heated from source 22. Cathode 36a and 5a are heated from source 9. Plate potential for electron tube 5 and electron tube 36 is supplied from source 14. Plate potential for electron tube 15, oscillator tube 26 and electron tube 45 is supplied from source 21. This provides an extremely compact arrangement of apparatus. The polarized relay 42 has a core structure 42a which actuates movable armature 53, coacting with sets of front and back contacts 54. A center lead 55 is taken from armature 53 while independent leads 56 and 57 are taken from front and back contacts 55 to provide the marking, timing and spacing contacts for connection to the Teletype or Baudot code apparatus. The back contact of the set of contacts 24 of polarized relays 12 connects through condenser 58 to one side of the input circuit of the audible frequency oscillator. The other side of the input circuit of the audible frequency oscillator connects through lead 59 to the movable armature 23. When armature 23 connects to the back contact of the set of contacts 24 the condenser 58 is placed in shunt with inductance 27, thus changing the period of oscillation of the audible frequency oscillator and changing the character of operation of the audible frequency oscillator 25 and effecting an operation of the second polarized relay system 42. Oscillations cease when armature 23 is restored to normal position, or so change in period as not to effect the operation of the polarized relay system 42 in the same direction as the original 105 keying operation, affecting the second polarized relay system. The operation of the audible frequency oscillator 25 is observed by the operator listening at telephones 61 connected through condensers 60 at points across resistance 30. Any 110 failure of the operation of the audible frequency oscillator is immediately detected in telephones 59 which respond to the audible frequency note generated by audible frequency oscillator 25 and permitting a check to be maintained upon the 115 operation of the audible frequency oscillator.

The operation of the two polarized relay systems is effected at high speed for the reason that the functioning of electron tube 15 is proportional to and coacts with the functioning of electron tube 5 while the functioning of electron tube 45 is proportional to and coacts with the functioning of electron tube 36. The reason for this will be apparent when it is noted that resistor 11 in the output circuit of tube 5 is disposed in the 120 input circuit of tube 15 so that when the polarity imparted to the grid circuit of tube 15 from the connection to resistor 11 goes positive to a great degree, the rise in plate current in tube 15 through actuating winding 20, enables actuating winding 120 20 to attract armature 23 while actuating winding 10, repels armature 23, and vice versa, thus giving positive high speed actuation to armature 23. That is to say, the operation of tube 15 is differentially related to the operation of tube 5 and is directly dependent upon the current flow through resistor 11 in the output circuit of electron tube 5. Similarly, armature 53 is controlled by the cooperative relation of actuating windings 125 40 and 50 due to the connection of the input circuit of tube 45 across resistor 43 which is in the output circuit of tube 36. As the degree of change in the positive potential applied to the grid 45b of tube 45 through its connection with resistor 43 increases, a change is effected in plate current 130 through actuating winding 50. Thus as the current through actuating winding 40 decreases, the plate current through actuating winding 50 increases so that while actuating winding 40 is 135 repelling armature 53, actuating winding 50 is 140

145 145 through actuating winding 50. Thus as the current through actuating winding 40 decreases, the plate current through actuating winding 50 increases so that while actuating winding 40 is 150 repelling armature 53, actuating winding 50 is 150

attracting armature 53, thus assisting in the rapid movement thereof for insuring faithful reproduction of the impulses delivered by the audible frequency oscillator.

- 5 Adjustments may be made of the grid potentials on each of the tubes 5, 15, 36, and 45, in order to insure precision operation thereof under control of high speed impulses. In the Baudot code it is highly important that the circuits respond at 80 high speed as the impulses in the Baudot code are close together and failure of the circuits to respond to any one of the impulses will be fatal to the satisfactory operation of the Baudot apparatus. The fact that adequate power is available 85 from the audible frequency oscillator which is keyed at the receiver, renders the operation of the Baudot code apparatus substantially independent of the relatively weak incoming signaling energy.
- 10 20 While I have described my invention in one of its preferred embodiments, I desire that it be understood that modifications may be made and that no limitations upon my invention are intended other than are imposed by the scope of the appended claims.

The invention herein described may be manufactured and used by or for the Government of the United States of America for governmental purposes without the payment of any royalty 90 thereon or therefor.

What I claim as new and desire to secure by Letters Patent of the United States is as follows:

1. In a signal receiving system, an audio frequency signal responsive circuit, a pair of blocked 35 grid amplifiers differentially connected with said circuit, a polarized relay having a winding disposed in each of said differentially connected blocked grid amplifiers, a set of contacts controlled by said polarized relay, an audio frequency 40 oscillator, connections from said contacts to said audio frequency oscillator for controlling the character of operation of said oscillator, a second blocked grid differential amplifier connected with said oscillator, and a relay controlled by said second 45 blocked grid differential amplifier, in accordance with signal impulses impressed upon said signal responsive circuit.

2. In a signal receiving system, a circuit responsive to audio frequency signal impulses, a 50 differentially connected amplifier connected with said circuit, a polarized relay operated by said amplifier, an audio frequency oscillator, connections to said oscillator controlled by said relay, a second differentially connected amplifier connected with said oscillator, a polarized relay operated by said second amplifier, and means connected with said oscillator and controlled by the 55 operation of said first mentioned polarized relay for rendering said oscillator effective upon said second mentioned polarized relay in accordance with signal impulses impressed upon said signal receiving circuit.

3. In a signal receiving system, an audio frequency signal responsive circuit, a differentially connected audio frequency amplifier electrically connected with said signal responsive circuit, a polarized relay having windings connected in the output of said differentially connected audio frequency amplifier, a second audio frequency differentially connected amplifier, a polarized relay 60 connected with the output of said second differentially connected audio frequency amplifier, an audio frequency oscillator and a circuit inter-

connecting said first mentioned polarized relay, said audio frequency oscillator, and the circuits of said second mentioned differentially connected audio frequency amplifier, for impressing signal impulses upon said second mentioned differentially connected audio frequency amplifier from said audio frequency oscillator in accordance with signal impulses received by said audio frequency signal responsive circuit.

4. A telegraphic signal receiving system comprising an audio frequency signal responsive circuit, a differential amplifier constituted by a pair of alternately operating electron tube circuits connected with said signal responsive circuit, a polarized relay having one winding thereof individual to the output circuits of each of said electron tubes, an armature controlling a set of contacts actuated by said relay windings, an audio frequency oscillator, a second differential amplifier comprising a pair of alternately operating electron tubes, a polarized relay controlled by said second differentially connected amplifier, and a circuit interconnecting the contacts of said first mentioned polarized relay with said audio frequency oscillator and with said second differentially connected amplifier for impressing impulses from said oscillator upon said second differentially connected amplifier in accordance with audio frequency signal impulses delivered by said signal responsive circuit.

5. A telegraphic signal receiving system comprising an audio frequency signal responsive circuit, a differential amplifier connected with said circuit, a polarized relay having a pair of actuating windings operated by said amplifier, an audio frequency oscillator, a second differentially operated audio frequency amplifier, a polarized relay actuated by said second differentially operated amplifier, a keying circuit interconnecting said oscillator with said first mentioned polarized relay, connections between the output of said oscillator and said second mentioned differentially connected amplifier, and a signal observing circuit connected with said oscillator for checking the character of signal impulses impressed by said oscillator upon said second mentioned differential amplifier in accordance with the signal impulses received by said signal responsive circuit.

6. In a signal receiving system, an audio frequency signal receiving circuit, a differential amplifier connected with said signal receiving circuit, said amplifier comprising alternately operating electron tubes, a polarized relay having windings connected with the circuits of said electron tubes, an audio frequency oscillator, a second differentially connected audio frequency amplifier constituted by separate electron tubes operating successively, a second polarized relay having its windings connected in the output circuits of said second differentially connected amplifier, a common source of power for the power circuits of corresponding tubes in each of said differentially connected amplifiers, and circuits interconnecting said audio frequency oscillator, said second mentioned differentially connected amplifier and said first mentioned polarized relay for impressing signal impulses from said audio frequency oscillator upon said second mentioned differentially connected amplifier under control of signal impulses impressed upon said signal responsive circuit.

JAMES M. KANE.
